UNITED STATES PATENT OFFICE.

HUGH L. SIMPSON, OF FORT DODGE, KANSAS.

DESIGN FOR AN ATTACHMENT FOR BABY-CARRIAGES.

53,106.

Specification for Design.

Patented Mar. 18, 1919.

Application filed January 10, 1919. Serial No. 270,597. Term of patent 3½ years.

To all whom it may concern:

Be it known that I, HUGH L. SIMPSON, a citizen of the United States, residing at Fort Dodge, in the county of Ford and State of Kansas, have invented a new, original, and ornamental Design for an Attachment for Baby-Carriages, of which the following is a specification, reference being had to the accompanying drawing, forming a part thereof.

The figure is a side elevation of a baby carriage attachment showing my new design.

I claim:

The ornamental design for an attachment for baby carriages, as shown.

HUGH L. SIMPSON.
